2 Claims. (Cl. 103—96)

This invention relates to a self-priming side channel centrifugal pump with more or less axial flow towards the suction slot. It aims at improving the air suction capacity of this pump.

For air suction or gas pumping respectively a side channel centrifugal pump makes use of a quantity of liquid which is retained in the pump casing by suitable means after the pump is shut off.

To renew operation this liquid must be guided into the stage designed for priming and must be retained in sufficient quantity in the pumping chamber during the whole priming period.

It is known that liquid is entrained and escapes out of said stage during the gas pumping process through the pressure slot, and special baffle plates and deflecting ribs have been provided in the pressure chamber to stow up this liquid in the side channel and to guide it back into said stage. Nevertheless the air suction capacity of this pump is still limited, since, as it has proved, during the gas pumping process liquid is also hurled through the suction slot back into the suction chamber and into the suction pipe and is thus lost for the pumping of the gas, with a worsening effect on the air suction capacity.

According to the invention there is provided a self-priming side channel centrifugal pump with more or less axial flow towards the suction slot and a covering element provided in front of the suction slot, characterised in that the covering element, forming a guide rib, in the rotational direction of the impeller wheel only covers the front part of the suction slot.

The purpose of this rib is to deflect liquid emerging from the impeller cells at the beginning of the suction slot during the gas pumping process and to guide it directly back to the impeller cells.

This obviously results in an essential improvement of the gas pumping capacity.

According to the invention it is further suggested to incline said rib towards the impeller wheel, seen in the direction of rotation (of the impeller wheel) and extend it quite close to it. This construction has been found particularly favourable.

A specific embodiment of the invention will now be described by way of example with reference to the accompanying drawings, in which:

FIGURE 1 is a longitudinal vertical sectional view, partly diagrammatic, taken on line 1—1 of FIGURE 2 through a pump built in accordance with invention.

FIGURE 2 is a transverse cross-sectional view taken on line 2—2 of FIGURE 1, and

FIGURE 3 is a detailed fragmentary sectional view taken on line 3—3 of FIGURE 2.

Referring more particularly to the drawings, on a shaft 1 is mounted an impeller wheel 2 which rotates in a casing formed by the casing components 3, 4 and 5.

The inflowing pumping medium flows through the suction branch 6 into the suction chamber 7 and there-

2

after through the suction slot 8 into the pumping chamber of the pump formed by the cells of the impeller wheel 2 and the side channel 9.

According to the invention a guide rib 10 is provided in front of the suction slot and forms a pocket which deflects the liquid emerging from the impeller cells during the air suction process, and then guides it back again to the impeller wheel. The position of the guide rib is shown more particularly in FIGURE 3. It covers, in the example shown, only the starting or upstream edge 12 of the suction slot and, is furthermore inclined towards the impeller wheel, seen in the direction of rotation of the impeller wheel (indicated by the arrow in FIG. 3) and extends quite close to the leading edges 13 of the radial blades 14 of the impeller wheel 2.

The packing 11 has the duty of sealing the shaft passing through the pump casing.

While the above specification sets forth the invention with reference to a specific embodiment, it will be understood by those skilled in the art that many modifications may be made without departing from the spirit and scope of the invention.

What is claimed is:

1. A self-priming side channel centrifugal pump comprising:
  - (a) a casing defining a suction chamber and an impeller chamber;
  - (b) a shaft journaled for rotation in the casing;
  - (c) an impeller wheel fixed on said shaft and disposed in the impeller chamber for rotation therein and having radial blades;
  - (d) a partition in said casing and separating said suction chamber and said impeller chamber;
  - (e) said blades being radially disposed in said impeller chamber and having radial leading edges facing said suction chamber;
  - (f) said partition being provided with a suction slot communicating said chambers, said slot having circumferentially spaced radially extending starting and ending edges closely adjacent the radial edges of the impeller blades, the starting edge being the upstream edge with regard to the rotational direction of the impeller wheel and
  - (g) a covering rib element defining an open pocket adjacent the impeller chamber extending from the upstream edge of the suction slot, said pocket having a cooperating surface that cooperates with the fluid that is recirculated by the impeller wheel and redirects the same back into the radial leading edges of the blades.

2. A pump as claimed in claim 1, wherein said surface is inclined toward the impeller wheel in the direction of the ending edge of the suction slot and is spaced a substantially small distance from the leading edges of the blades.
